UNITED STATES PATENT OFFICE

110,318

DESIGN FOR A DOILY OR SIMILAR ARTICLE

George Henry Shamyer, New York, N. Y.

Application June 2, 1938, Serial No. 77,527

Term of patent 3½ years

To all whom it may concern:

Be it known that I, George Henry Shamyer, a citizen of the United States of America, residing in New York city, in the Borough of Manhattan, county and State of New York, have invented a new, original, and ornamental Design for a Doily or Similar Article, of which the following is a specification, reference being had to the accompanying drawing, forming part thereof, wherein, the figure is a plan view of a doily or similar article showing my new design.

I claim:

The ornamental design for a doily or similar article, substantially as shown.

GEORGE HENRY SHAMYER.
